UNITED STATES PATENT OFFICE.

HUGO STÄUBLI, OF ZURICH, SWITZERLAND, ASSIGNOR TO GEBR. STÄUBLI & CO., OF HORGEN, SWITZERLAND.

SHED-FORMING MACHINE WITH PAPER PATTERN CARDS.

Application filed March 17, 1927, Serial No. 176,174, and in Switzerland May 28, 1926.

A shed-forming machine for the manufacture of fabrics with long repeats of weft threads, whether it be a dobby or a jacquard mechanism, needs for advantageous working, a pattern-card of paper. A dobby with paper pattern cards up to to-day worked positively only in one way, that is to say while running forwards. A dobby with lags and pegs in comparison already 5 works positively in both directions, that is to say, if the loom runs forwards or backwards the sheds are always opened in the right sequence; thus for a pickout, the weaver only had to turn the loom backwards without any manipulation of the dobby mechanism. A paper pattern dobby has the advantage over a dobby working with wooden lags and pegs of allowing the 10 weaving of fabrics with very long repeats, up to 10000 picks per repeat. To weave such a fabric with wooden lags and pegs is practically impossible. The paper pattern which I use for my dobbies may 15 contain for instance 333 picks per meter and even a long pattern can easily be placed in such a manner that it will not be inconvenient either for the good working of the machine or for the space required. The great 20 advance of the new type dobby working with paper pattern over the old type is the positive motion of the pattern cylinder in both directions. This enables the weaver to turn the loom backwards for a pickout without any manipulation of the dobby mechanism; 25 the right shed in relation to the pattern will always be opened. The shed-forming machine for dobby or jacquard-mechanism constituting the subject-matter of the present 30 invention, furnishes both during its forward movement and also during the return movement a weaving-in and releasing respectively of the wefts in the correct sequence. This is based upon the fact that 35 during one stroke of the lifting knife or knives, two successive picks of the pattern-card for the same knife are read off at the same time and the hooks are placed and kept in readiness for the lifting knife by 40 suitable members in such a way that during the lost motion of the knife, when the machine is rotating forwards, the coming pick is the determining factor, and during the 45 backward rotation the preceding pick is the

determining factor, for the position of the 55 hook in relation to the knife.

The accompanying drawings illustrate two constructional examples of the invention constructed as dobbies.

Figures 1 to 3 being diagrammatical 60 views of the first example, which relates to a single-lift dobby.

Fig. 4 is a graphic chart showing the movements of the elements of the machine 65 disclosed in Figs. 1 to 3.

Fig. 5 is a similar graphic chart showing the elements of the machine shown in Figs. 6 to 9.

Fig. 6 shows part of this second example 70 in front elevation,

Fig. 7 shows a section on the line A—B in Fig. 6, with individual parts located in front of the plane of section,

Fig. 8 shows a section taken in the same 75 plane but on a smaller scale, with the movable parts in a different position,

Fig. 9 is a partial side elevation of the machine, showing the driving elements of the cylinder motion which are also shown 80 in front elevation in Fig. 6.

In the constructional example according to Figs. 1 to 4, 1 is the cylinder over which the paper pattern-card 2 runs, and which is fed forward one pick from the shaft 5 after each pick of the loom by transmission elements which are more fully indicated for the second example in Figs. 6 to 9. Upon the shaft 5 is mounted, in a manner known from existing dobbies, at each end of the machine, a cam disc 6, which through the medium of a 90 roller 8, actuates an oscillating arm 10, which carries the lifting knife 12. Within reach of the latter are located the hooks 14, each connected with one end to a balance 40 whilst the other end lies free. The balance engages 95 with a swing 41, which is movably mounted upon a rod 42 and to the arm 43 of which a shaft is connected in a known manner. In the positions according to Figs. 2 and 3, the balance 40 bears against stationary ledges 44. 100

Under each hook 14 is mounted loose upon a rod 17 a thin bell-crank lever 16, which is subject on the one hand to the influence of a tension spring 18, and on the other hand to that of two driver needles 21^a and 21^c. 105 From each of the latter there hangs a needle, 22^a and 22^c respectively, for reading the pattern-card. The needles 22^a and 22^c are

located at the weft distance one behind the other, in order that two successive picks may always be simultaneously read off by them. They are guided in iron strips or ledges 23, and the driver needles 21^a and 21^c are guided in the vertical limb of an angle iron 24, a horizontal limb of which serves as a stop for the levers 16 if the latter are only subject to the action of the springs 18.

10 For lifting the reading needles 22^a and 22^c off the paper card 2 before the feeding of the reading needles, and for the subsequent supporting of those driver needles 21^a and 21^c of which the needles 22^a and 22^c have dropped into holes in the paper card, there serve bars 25 and 26 respectively, which are carried by the upper arm of a bell-crank lever 28, the other arm of which is pressed by gravity against the periphery of a cam 29. The latter revolves at the same speed as the cam shaft 5. Upon a shaft 4, which likewise revolves with the velocity of the shaft 5, and which therefore in practice will preferably be the shaft of the cam 29, are mounted two cams 30 and 31 with their tops angularly displaced in relation to one another. Of these, the cam 30 acts upon a bell-crank lever 32, and the cam 31 upon a similar bell-crank lever 33. The other upwardly directed arms of these bell-crank levers 32 and 33 each carry a driving bar, 34 and 35 respectively, which act in a manner to be described below upon the driver needles 21^a and 21^c.

25 The diagram given in Fig. 4 illustrates the movements of the elements described, in their relative time relationships during the revolution of the cam shaft 5. Figures 1 to 3 illustrate the relative positions of these elements in relation to the points I, II and III on the diagram. In the latter, the vertical lines provided at the top with degree indications denote the various positions of the cam disc 6 beginning in the position according to Fig. 40. The numbers applied to the transverse lines correspond to those which are used in Figures 1 to 3 for the members, the movements of which are represented by those lines.

45 From this diagram will be seen, starting from the left, before the position of the cam disc 6 marked 0°, the following:—

50 While the roller 8 bears upon the beginning of the longer left-hand concentric peripheral part of the cam disc 6 in Fig. 1, the knife 12 is stationary, and before the cylinder 1 is fed forward, the needles 22^a and 22^c are lifted out of the paper card 2, the eccentric part of the cam disc 29 rotating the lever 28 in such a way that the small rods 25 and 26, and the driver needles 21^a and 21^c bearing upon them, are raised. The needles 22^a and 22^c are thus located during the feeding movement of the cylinder 1, which immediately succeeds their upward movement,

out of contact with the paper card, as shown in Fig. 1. After the feeding of the cylinder is completed, the top of the cam 29 slips off the lever 28, and thus the small rods 25 and 26, the driver needles 21^a and 21^c and the needles 22^a and 22^c descend, so that the latter can now read two successive picks.

55 In the following constructions it is first assumed that under each needle there is a hole in the paper card 2. Hence the needles 22^a and 22^c drop into the latter, the depth of penetration being regulated by the bearing of the driver needles 21^a and 21^c upon the small rods 25 and 26 which are held stationary by the lever 28 as long as the concentric 70 part of the cam 29 lies on the lever 28.

With their downward movement the driver needles 21^a and 21^c pass within reach of the driving bars 34 and 35. As a result, the top of the cam 30 first comes into action 85 upon the lever 32 in such a direction that the driving bar 34 is pushed forward and thereby pushes forward the driver needle 21^a. The lever 16 is thereby rotated backwards against the action of the spring 18, so that 90 it does not touch the hook 14, which at the same time (Fig. 4) swings backwards and downwards out of the position indicated in Fig. 1. This hook therefore remains lying upon the lifting knife 12. The position of 95 the parts is now that indicated in Fig. 2. Here begins the so-called lost motion of the knife 12, that is to say, the latter continues its previous movement backwards a little further, while the roller 8 bears 100 upon a part of a cam disc 6, the distance of which from the axis of rotation decreases somewhat further in the direction of rotation. The hook 14 on the contrary no longer follows this movement of the knife 12, as the balance 40 bears on both ledges 44. The position of the parts 16, 32, 34 and 21^a at first still remains the same. As soon, however, as the top of the cam 30 begins to run off the lever 32 the driving bar 110 32 moves back again and therefore the lever 16 can rotate forwards under the action of the spring 18 not however into its initial position, but only into an intermediate 115 position in which it somewhat raises the hook 14 (Fig. 3), for if the end of the lever 32 that bears upon the cam 30 has moved back as far as half the height of the cam, the end of the lever 33 bearing upon the cam 31, has in its ascent reached half 120 the height of the cam in question. While therefore from this position onwards (Fig. 3) the driving bar 34 goes back, the driving bar 35 swings further forward, and, by means of the driver needle 21^c, rotates the lever 16 back again. The hook 14 thus places itself again upon the knife 12 and is driven by the latter, which has meanwhile 125 commenced its forward movement.

130 Subsequently the driving bar 35 also re-

turns to its initial position again, releasing the driver needle 21^c, and the cam 29 again actuates the lever 28 in such a direction that it raises the small rods 25 and 26 and thereby 5 brings the needles 22^a and 22^c out of reach of the paper card 2. The cylinder 1 is then fed forward one pick, and the cam disc 5 begins its second revolution, whereupon the operations described are repeated, but the 10 pick previously read by the needle 22^c is read by the needle 22^a, and the needle 22^c reads a new pick. Hence, each pick is read twice.

It was assumed above that each of the needles 22^a and 22^c had dropped into a hole in 15 the pattern-card. Should, however, only the needle 22^a for example have dropped and not the needle 22^c, because the paper card 2 contained no hole at the point in question, the following modification would take place:—

20 The driver needle 21^c, during the transition of the lever 28 out of the position according to Fig. 1 into that according to Fig. 2 in consequence of the needle 22^c standing up on the paper card 2, could not 25 follow the descending rod 26 into its lowest position, but owing to the needle 22^a, would remain stationary on the way in such a position that during the oscillation of the lever 33 it would not be touched by the 30 driving bar 35. Hence the lever 16 could follow the driver needle 21^a returning to its initial position as far as the stop on the angle iron 24, and would lift the hook 14 completely off the knife 12, so that the latter 35 would execute the second half of its travel idly, that is to say the corresponding shaft would not be lifted.

From Fig. 3 and position III in Fig. 4 it will be seen that if the machine is rotated backwards out of this position the 40 driving bar 34 moves back again (towards the right in Fig. 3) and pushes the lever 16 away from the hook 14, so that the latter is driven forward by the knife 12 in its 45 movement, and thus the immediately preceding pick is released again. At the moment when the knife 12 is located in its basic position (Fig. 3) there are always two picks available for the hanging of the 50 hook 14 on the knife, and as a consequence one pick is woven in, or the other pick released again according to the direction of rotation. With a constant direction of rotation of the machine the said same is transferred to the lever 16 the first time by the 55 first needle (22^c for example) during the second half, and the second time, after the cylinder has been fed forward, by the second needle (22^a for example) during the 60 first half of the lost motion of the knife. Under these circumstances, however, only the transmission occurring in the second half of the lost motion is on each occasion a determining factor for the hanging of the 65 hook on the knife.

As will be seen from Fig. 4 the movement of the driving bars 34 and 35 occupy a somewhat greater interval than the lost motion of the lifting knife. One driving bar has already reached its outermost working position before the lost motion commences and only after the termination of the latter does the other driving bar return back out of its working position. A guarantee is thereby given that the hook 14, at the beginning 70 and at the end of the lost motion, lies upon the knife, so far as the corresponding needle 22^a or 22^c is located in a hole in the pattern-card, or is lifted off the knife, not hung, in so far as this needle has not found a hole. 75

In the case of the constructional form (double-lift machine) according to Figs. 5 to 9, the operations described for one knife in reference to Figs. 1 to 4 take place in a similar manner for each of the two knives. 80

While, however, in the case of the single-lift machine the cylinder of the paper pattern-card is fed forward one pick after each pick, in the case of the double-lift machine the feeding of the cylinder takes place after 85 every second pick through two picks, the holes in the paper card corresponding to these two picks and therefore also the associated needles, being displaced a few millimeters from one another in the longitudinal and transverse directions of the paper card. The shafts 4 and 5 revolve in the case of the double-lift machine only half as fast as in the case of the single-lift machine and at 90 the same speed as one another. 6 and 7 (Fig. 9) are the cam discs mounted on the shaft 5, and 8 and 9 the rollers bearing 95 against the discs and carried by the knife levers 10' and 11. 12 is the lower lifting knife, and 13 the upper lifting knife. 14 and 15 are the hooks, one upper and one lower of each of which engage with the same balance 40. Upon the lower hooks 14 there acts the lever 16', and upon the upper hook 15 a lever 20, mounted loose on the 100 same pivot 17 as the lever 16', through the medium of a thin rod or wire 19, the lower end of which bears upon an oblique surface on the upper end of the lever. Like the lever 16', the lever 20 is also subject to the 105 action of a tension spring 18, which might likewise be replaced by a counter-weight. As in the case of the first example, the lever 16' is here again subject to the influence of two driver needles 21^a and 21^c, while upon 110 the lever 20 there act the two driver needles 21^b and 21^d located one above the other in a vertical plane, the needles 22^b and 22^d being suspended from the said drivers 21^b and 21^d. The needles 22^b and 22^d are located 115 in a plane which is parallel to the plane passing through the needles 22^a and 22^c and are set back a few millimeters in the peripheral direction of the cylinder 1 relatively to 120 the said needles. It is assumed that the 125

130

needles 22^a and 22^c read the odd picks (indicated at the bottom of Fig. 6 by way of example by the holes marked *a* and *c* in the paper card 2), while the needles 22^b and 22^d read the even picks (for example *b* and *d* in Fig. 6). For the supporting of the driver needles 21^a, 21^b, 21^c and 21^d there serve, as in the case of Figs. 1 to 3, small rods 25 and 26 carried by arms 27 of a bell-crank lever 28, the rod 25 serving for the driver needles 21^a and 21^b and the rod 26 for the driver needles 21^c and 21^d. The lever 28' in its turn is subject to the influence of the cam 29 mounted fast upon the shaft 4. The cams 30' and 31' likewise secured to the shaft 4 each comprise two diametrically opposite rises. The relationship between the positions of one rise on one cam disc and the adjacent rise on the other cam disc, and that of one of these pairs of rises and the rise on the cam disc 29, is similar to what has been described in reference to Figs. 1 to 3. The arrangement of the bell-crank levers 32 and 33 and of the driving bars 34 and 35 carried the latter in the case of this constructional form of the machine is similar to their arrangement in the previous case. Each of the driving bars acts upon two levers 16' and 20, namely the bar 34 by the driver needles 21^a and 21^b, and the bar 35 by the driver needles 21^c and 21^d.

The method of working of the machine illustrated in Figs. 6 to 9 is in part evident from what has been said in reference to Figs. 1 to 4, and the remainder will be explained in reference to the diagram contained in Fig. 5. In Fig. 5 the degree indications arranged in a row at the top again relate to the cam shaft 5, while the numbers applied to the transverse lines indicate that these lines represent the movements of the similarly designated members. The positions marked in Fig. 5 as I, II and III correspond to the similarly designated positions according to Fig. 4, with the differences conditioned by the other number of knives. Thus for example in position I in Fig. 5 the knives are in motion and cross one another. From this position onwards, which is also illustrated in Fig. 8, the movements of the various parts proceed essentially in the following manner:

The knife 12 moves backwards, the knife 13 forwards, (see arrows in Fig. 8). The cam 29 by its projecting part has rotated the lever 28' in such a way that the upper arm 27 thereof has raised the small rods 25 and 26, and thereby the driver needles 21^a, 21^b, 21^c and 21^d, and the needles 22^a, 22^b, 22^c and 22^d into the position indicated in full lines in Fig. 8, so that all the latter stand above the cylinder 1, that is, out of contact with the paper card-pattern 2, when the latter is now fed forward. This feeding is effected after every second pick, that is, for every

complete revolution of the cam plates 6 and 7, once by two picks (one pick for each knife) by means of a tooth 45 (Fig. 9), which is mounted fast upon the shaft 4 and which engages with a toothed wheel 3 mounted fast upon the shaft of the cylinder 1. When this feeding is completed, the cam on the cam disc 29 slides off the lever 28, the upper arm 27 of the latter descends, and the needles 22^a, 22^b, 22^c and 22^d are now released for the reading of the pattern-card 2. In the following remarks it is assumed by way of example that the pattern-card contains holes in its present position underneath the needles 22^a and 22^c, but not underneath the needles 22^b and 22^d, the position thus being as indicated below in Fig. 6 by the letters *a*, *b*, *c*, *d*, for a later position. Thus the needles 22^a and 22^c can drop into the pattern-card 2, and the driver needles 21^a and 21^c follow the descending small rods 25 and 26 and pass within reach of the driving bars 34 and 35, as shown in dot-and-dash lines in Fig. 8. Immediately after the projecting part on the cam disc 29 has run off the lever 28', the adjacent cam on the cam disc 30 comes into action upon the lever 32, so that the driving bar 34 pushes back the driver needle 21^a and the latter pushes back the lever 16' into the position according to Fig. 7. The lever 16' therefore comes out of reach of the hook 14 swinging back, so that the latter remains lying upon the knife 12, when it begins its lost motion (Fig. 7). While in the course of this lost motion the cam on the disc 30 runs off the lever 32, the adjacent cam on the cam disc 31 begins to act upon the lever 33, as has been described above with reference to Figs 1 to 4. The lever 16', when the movement of the knife 12 reverses is therefore held in the disengaged position (Fig. 7) by the driving bar 35 and the driver needle 21^c. The hook end therefor remains hanging on the knife 12 and is carried forwards by the latter in its movement. The above-described actuation of the levers 32 and 33, the driving bars 34 and 35, the driver needles 21^a and 21^c, and the lever 16' is repeated after half a revolution of the shaft 4 under the action of the second cam on the cam discs 30', 31', without however having here any significance, as the knife 12 is now located in its front end position. On the other hand the upper knife 13 has meanwhile reached its rear position. As, however, the needles 22^b and 22^d could not enter holes in the pattern-card, the parts 21^b and 21^d, 20 and 19 maintain the positions indicated in Fig. 7, so that the hook 15 remains in its raised position and cannot hang on the knife 13. If, however, the needles 22^b and 22^d had been able to drop into holes in the pattern card, operations would have taken place under the action of the second cam on the cam discs 30 and 31 at the rear

end of the path of the knife 13, similar to those described above for the lower knife 12. The driver needles 21^b and 21^d would have been located in the same position as regards depth as is indicated in Fig. 7 for the needles 21^a and 21^c. They would therefore have come into contact during the swinging of the levers 32 and 33 with the driving bars 34 and 35 and would thereby disengage the lever 20, so that the rod 19 and with it the upper hook 15 could descend. The latter would accordingly hang on the knife 13 and be carried with it in its forward movement. In the following crossing of the lifting knives in the direction indicated by Fig. 8 the cylinder 1 is fed forward by two picks, that is to say by so much that the hole in the pattern-card 2 previously located below the needle 22^c has come to lie below the needle 22^e. Hence if during the preceding stroke of the knives the first and third picks were read off by the needles 22^a and 22^c and the second and fourth picks by the needles 22^b and 22^d, it would now be the third and fifth and the fourth and sixth. Here again, as in the case of the single-lift machine, each pick is read off twice, and in the case of one knife it is always the even picks, and in the case of the other knife the odd picks. One of the supporting levers 16', 20, comes into action for the even picks, and the other for the odd picks. According to the direction in which the loom or the shed-forming machine is fed forward one or other of the picks standing ready for the same knife comes into operation. Hence, with this machine forward or backward rotating can be effected from any desired point and the correct pick will always work.

If a dobby shall work with positive motion, it is essential that, in relation to one knife, the respective hooks of different shafts change during that short interval during which the knife remains at its dead position, as shown for instance in Fig. 3. If for instance a shed is formed by lifting the 1st, 3rd, 5th and so on shafts, while the even shafts remain in their lower position, for the first pick, and afterwards, for the second pick the odd shafts remain low while the even shafts are lifted, the respective hooks have to be pulled forward by the knife. For the first pick the odd hooks will fall down upon the knife while the even hooks will be retained out of reach of the knife 12 by their supporting levers 16. Then the knife 12 is going forward, actuating the first pick. After its return to the dead point position, the changing of the hooks has to be actuated; that is to say, the odd hooks must be brought out of reach of the knife by their supporting levers 16, while the even hooks must fall down upon the knife to be pulled forward, thus opening the second shed for the second pick. This

changing of the hooks must be done while the knife is in its dead position; therefore, if the direction of the running of the loom is changed, the hooks 14 for the first shed will be released and fall down again upon the knife, while the hooks for the second shed will be brought out of reach of the knife. Now then, to enable this manipulation of the hooks, the respective supporting levers 16, Fig. 3, for instance, must be kept ready in this moment, to either release or lift the hooks out of reach of the knife. At the same moment, there must be two picks be read off by the needles 22^c and 22^e respectively; that is to say, the first pick and the second pick; let us say that the first pick has already been woven, and that the second one is going to be woven. Now then, if the loom runs forwards the second pick being read off by the needle 22^c, Fig. 3, the driving needle 21^c is pushed forwards, because of the cam 31 and driving bar 35, against the spring of the lever 16 and so releases the hook. The same processes have been done for the first pick before and by the same needles etc. If now starting from the point shown in Fig. 3, the loom has to be rotated backwards, the shed for the pick No. 1 must be opened again. The shaft 4 will turn in the opposite direction as indicated by the arrow, thus the cam 30 will act upon the lever 32 and therefore push forwards the driving needle 21^a, which this time releases the hook 14 by turning the lever 16 backwards against the power of the spring. For this reason there are arranged two needles.

If in the contrary, there would be used one feeler needle 22 only, the following processes would have to be done. Supposing the first pick has been woven and the knife has come back to its dead point position as shown in Fig. 3, the feeler needle, at this moment, would be fallen down upon the paper card in order to read off the second pick. If now the direction of the running of the loom and dobby were changed in order to open again the first shed for picking out the first pick, the feeler needle would have to be lifted out of the paper, the cylinder would have to be turned backwards to bring the first pick underneath the feeler needle, which then would have to be let drop on the paper card in order to read off the first pick. But for all these processes, the lapse of time, during which the knife remains in the position shown in Fig. 3 is too short; a fact fully proven by the existing machines. As the feeding of the pattern cylinder only takes place after every second pick, but takes place by two picks each time, the machine works smoothly.

What I claim is:—

1. A shed forming machine, comprising movable hooks for lifting the threads of the

warp, a lifting knife adapted to engage with such hooks and to perform a reciprocating movement together with the hooks engaged with it and a short movement relatively to these hooks just before reaching and after having reached one of its dead points, a movable pattern card, movable pick reading members adapted to come in engagement with this card for reading a pick, movable members adapted to adjust the position of the lifting hooks to the pattern as represented on the pattern card during said period of relative movement of the lifting knife in such a way that on the subsequent stroke of this knife an engagement of hooks by the knife in accordance with the pattern will take place at either direction of working of the machine.

2. A shed forming machine, comprising movable warp lifting hooks, a lifting knife adapted to perform a reciprocating movement together with such hooks and a short movement relatively to these hooks at the end of the shaft lowering stroke and the beginning of the shaft lifting stroke, a movable pattern-card, pick-reading members adapted to be brought in contact with this pattern card while it is at rest, movable members adapted to support the lifting hooks during the period of idle movement of the lifting knife so as to hold said hooks out of reach of this knife, driving and releasing members dependent as to their relative position and operation upon the position of the pick-reading members relatively to the pattern-card and adapted to release said supporting members from their lifting hooks during said idle motion of the lifting knife at a definite position of the corresponding pick reading members to permit the released hooks to be carried along with this knife on its subsequent stroke.

3. A shed forming machine, comprising a movable-pattern-card, pick representing marks thereon, pick-reading members adapted to read off two successive picks from this pattern-card, movable lifting hooks for lifting the warp threads, a lifting knife adapted to perform a reciprocating movement, a movable member for each lifting hook adapted to support this hook at a definite period of the reciprocating movement of the lifting knife to hold it out of reach of said knife, driving means adapted to act upon said supporting member for releasing it in said definite period but dependent as to their operation upon the position of the pick reading members relatively to the pattern-card in such a manner that in either direction of working of the machine the hook is permitted to be carried along with the knife at its subsequent stroke if the corresponding pick reading member is in its reading position.

4. A shed forming machine comprising

movable warp thread lifting hooks, a lifting knife adapted to temporarily engage with such hooks and to perform a reciprocating movement with the hooks engaged and a short idle movement relatively to these hooks just before reaching and after having reached one of its dead points, a cylinder, a pattern-card on this cylinder, pick-representing marks on this card disposed in planes at right angle to the axis of the cylinder, pick reading members disposed at a distance one from another equal to the weft distance as given on the pattern-card in the same of said planes and to coact with said marks, means for displacing the pattern-card intermittently each time for a length equal to the weft distance in such a way that, according as to the direction of displacement, one or the other of said pick-marks is in position to be read by the other one of said pick-reading members than it was read before said displacement took place, driving members adapted to coact with the pick reading members in such a way that in said dead point of the hook lifting knife the driving members of both pick reading members are in position of readiness to permit the hook to come in reach of the lifting knife at the subsequent stroke thereof.

5. A shed forming machine, comprising warp lifting hooks, a lifting knife, driving means for imparting to this knife a reciprocating movement, a movable supporting member for each of said hooks adapted to control the position of such hook at definite periods of the reciprocating movement of the lifting knife, a movable pattern-card, pick-reading means adapted to coact with this pattern-card, driving means adapted to move in a determined speed ratio with regard to the lifting knife motion transmitting members disposed between these driving means and the hook supporting member and controlled by the pick-reading members in such a manner that in said definite periods of the reciprocating movement of the lifting knife said lifting hooks are either released by their supporting member to be engaged by the knife in its forward stroke or held out of the path of said knife according as the pick reading member corresponding to the actual direction of movement of the machine is in or out of engagement with the pattern-card.

6. A shed forming machine, comprising movable warp lifting hooks, a lifting knife adapted to perform a reciprocating movement and to impart to said hooks a lifting motion, a movable supporting member for each lifting hook adapted to hold this latter out of engagement with the lifting knife during a definite period of its movement, a movable pattern-card, pick presenting marks thereon, movable pick-reading members adapted to coact with two successive ones of

said marks, driving members adapted to be operated during said periods of the movement of the lifting knife, movable releasing members dependent as to their releasing operation upon the position of the pick reading members and interposed between said driving means and the hook supporting member in such a manner that when one of the pick reading members is in its pick reading position the corresponding releasing member is operated upon by said driving means to release said hook supporting member from the hook during a definite part of said period to allow the hook to be engaged by the knife to perform its warp-thread lifting motion.

7. A shed forming machine, comprising movable hooks for lifting the warp threads, a lifting knife adapted to engage with such hooks in a definite position thereof and to perform a reciprocating movement together with the hooks engaged with it to alternately lift and lower the corresponding warp threads and a short movement relatively to these hooks before reaching and after having reached its rear dead centre, a movable pattern-card, movable pick-reading members adapted to coat with this pattern card while it is at rest so as to read simultaneously two picks therefrom, of which picks one was read at the preceding feeding position of the pattern-card, and the other is read again at the subsequent feeding position, a movable supporting member for each hook controlled by the two pick reading members and adapted to act upon the lifting hooks during the idle motion of the lifting knife.

8. A shed forming machine, comprising movable warp lifting hooks, a lifting knife adapted to engage with such hooks and to perform a reciprocating movement together with the hooks engaged with it and a short idle movement relatively to these hooks just before reaching and after having reached its dead point at the beginning of the hook engaging stroke, a movable pattern-card, means for intermittently displacing this pattern-card for the weft distance, movable pick reading members hanging above the pattern-card at a distance on behind another equal to the weft distance as represented on the pattern-card and adapted to come in contact with this card while it is at rest, means for lifting these pick reading members and holding them removed from the pattern-card during the displacement of the latter, rocking levers for supporting the lifting hooks during the idle movement of the lifting knife, releasing members controlled by the pick-reading members to release said rocking levers from the hooks if the corresponding pick reading member is in its operative position.

9. In a shed forming machine, a rotatable

cylinder, a perforated paper pattern-card supported by this cylinder and adapted to run with it, means for intermittently displacing this pattern card each time for a length having a definite relation to the weft distance, two series of pick reading members located one behind another at a distance having a definite relation to the weft distance, always a member of the first and one of the second series being located in the same radial plane of the cylinder, a lifting knife, means for imparting to this knife a reciprocating movement, a series of warp lifting hooks adapted to be brought into reach of this knife, means for stopping the movement of the hooks on the rear end of its backward stroke before the knife is reaching its dead point, a movable supporting member for each of said hooks adapted to hold the hook out of reach of the lifting knife during the lost motion of the lifting knife, two actuating members for each of these supporting members adapted to be brought in working or non working position in accordance with the position of the corresponding pick reading members in such a manner that a hook, during one-half of the lost motion of the knife, is dependent upon one pick, and during the other half of the said lost motion, with constant direction of the machine, is dependent upon the other of the picks read, but in the event of a change in the direction, again becomes dependent upon the first pick.

10. A shed forming machine as claimed in claim 9, comprising a shaft for actuating the lifting knife, another shaft adapted to rotate in a definite speed ratio to the first shaft, two cams on this second shaft with their tops angularly displaced in relation to one another, a motion transmitting member in the reach of each of these cams and adapted to transmit the motion received therefrom to a member acting upon a hook supporting member in such a manner as to release it from the hook and giving this latter free to hang on the lifting knife.

11. A shed forming machine comprising a pattern-card, a revolving shaft, a lifting knife connected with this shaft so as to receive from it a reciprocating movement, lifting hooks adapted to come in reach of this knife, two series of pick reading members adapted to coat with the pattern-card, a transmission gear actuated by said shaft, two other shafts in this gear one thereof having the same speed as the first shaft, the other receiving an intermittent motion to displace the pattern-card each time by an amount which is in a definite relation to the distance of two series of pick reading members, wherein a rocking lever below each of said lifting hooks normally held in a position to raise the corresponding hook out of reach with the lifting knife during the dead

motion of the latter, two cams revolving with the same speed as the first mentioned shaft and having their tops angularly displaced in relation one with another, two bell-crank-levers each in the reach of one of these tops, two driver needles opposite each hook supporting rocking lever, the position of these driver needles being dependent on that of the pick reading members in such a manner that they are brought into reach of the corresponding bell-crank-lever if the corresponding pick reading member is in engagement with the pattern-card but are retained out of said reach when no such engagement takes place.

12. In a shed forming machine, a lifting knife adapted to perform a reciprocating movement, hooks pivotally connected with one end to a movable shed supporting member and extending in the direction towards and over the lifting knife, a movable supporting member for each of said hooks adapted to normally hold the hook out of engagement with the lifting knife during a definite period of the reciprocating movement of this knife, releasing members adapted to release the hook supporting member from the hook so as to allow this to fall in reach of the lifting knife and to be carried along therewith, means for stopping the backward movement of the hook before the lifting knife reaches its rear dead point, movable pick reading needles each controlling the position of one of said releasing members, a bell crank lever for each of these releasing members adapted to impart to each a releasing motion when the corresponding pick reading needle is in its pick reading position, a cam adapted to revolve in a definite velocity ratio to the lifting knife and to act upon said bell crank lever at a definite part of the idle motion of the lifting knife, the two cams which act upon the same hook supporting member being displaced relatively to one another in the peripheral direction in such a way that according to the direction of motion of the machine one comes into action upon the supporting member during the first and the other during the second half of the lost motion of the knife or conversely, and in the basic position of the knife, in the case of either direction of motion of the machine, both cams stand ready to release the supporting member.

13. In a shed forming machine according to claim 12, a movable pattern-card, a hook supporting lever rotatable about a horizontal axis, two driver needles opposite to this lever on the same side thereof, a pick reading needle hanging down from each of these driver needles, these two needles being disposed to read two successive picks in the direction of feed of the pattern-card, and, according as they can drop into holes in the

pattern-card or not, to bring the driver needles under the influence of one of said two cams or keeping them out of the range of action of the latter, one driver needle in the first case rotating the lever away from the hook during the first and the other during the second half of the lost motion of the knife, and thereby releasing the said hook for hanging on the knife, whereas in the second case the driver needles remain un- 75 actuated.

14. In a shed forming machine, a perforated movable pattern-card, a shaft, a lifting knife adapted to receive a reciprocating movement from this shaft, thread warp supporting hooks adapted to be brought in engagement and to be carried along with the lifting knife on its forward stroke, means for arresting the hooks at a certain distance in front of the rear dead centre of the knife 85 in order to permit this latter to perform a short idle motion in each direction near its rear dead centre, a supporting rocking-lever mounted below each of said hooks and holding the corresponding hook normally 90 out of engagement with the lifting knife during the idle motion of the latter, two driver needles opposite said supporting lever on the same side thereof, pick reading members controlling the position of the driver 95 needles in accordance with the pick holes in the pattern-card, a lever opposite each of said driver needles, a cam for each of these levers adapted to revolve in a definite velocity ratio to the shaft actuating the lifting 100 knife and to act upon said lever in such a manner that this lever, by means of the corresponding driver needle, releases the hook supporting lever, as far as the driver 105 needle is within the reach of said pushing lever, in order to permit the hook to be engaged by the knife on its forward stroke, said cams being so arranged that they actuate their pushing levers successively and that in the rear dead centre of the lifting knife 110 both pushing levers, one on its rearward and the other on its forward movement are located at half travel in a position ready to act upon their driver needle, the interval 115 within the two cams act being as a whole somewhat greater than the interval within which the lifting knife executes its idle movement.

15. A shed forming machine, comprising a perforated paper pattern-card, a cylinder 120 supporting this pattern-card, a lifting knife adapted to perform a reciprocating movement, a series of movable warp-thread lifting hooks located above the lifting knife and adapted to come in reach thereof to be carried along with this knife at its forward stroke and to follow its rearward stroke, means for stopping the rearward stroke of these hooks before the lifting knife reaches its rear dead centre, a rocking lever located 125 130

below each of said lifting hooks and adapted to normally hold the corresponding hook removed from the path of the lifting knife, two series of pick reading-needles hanging 5 above the pattern-card supporting cylinder in a distance one from another equal to a weft distance as represented on the pattern-card, a cam adapted to revolve in a definite relation with the lifting knife, a rocking lever in contact with this cam, two series of 10 driving needles supported by this rocking lever and supporting the pick-reading needles, a driving needle of one series and a needle of the other series being disposed on 15 the same side of the same hook supporting rocking lever, two other cams adapted to rotate with the said speed as the first mentioned cam, a rocking lever in reach of each of these two other cams adapted to act upon 20 the driving needles of one series at a definite position of the pick reading needles hanging thereon, these cams being so displaced relatively to one another in the peripheral direction that in the rear dead centre of the 25 knife the two rocking levers, one on its rearward and the other on its forward movement, are located at half travel in a position of readiness to push the driving needles towards the hook supporting lever to allow 30 the hook to fall in reach of the lifting knife at its subsequent forward stroke if the corresponding pick reading needle is in its pick reading position, the peripheral extent of said pair of cams as a whole being such 35 that the interval within which the two cams act is somewhat greater than the interval within which the knife executes its idle movement.

16. A shed forming machine as claimed in 40 claim 15, comprising a cam for imparting to the lifting knife a reciprocating movement, three other cams adapted to revolve at the same velocity as this first cam and displaced relatively to one another in the 45 peripheral direction, three bell crank levers each extending into reach of one of these last mentioned cams, the driving needles supporting the pick reading needles being supported by the same of said bell crank levers 50 and adapted to come into reach of and to be pushed by one of the other bell crank levers when the corresponding pick reading needle is in its lowermost or pick reading position, the cam acting upon the first of said bell 55 crank levers being located with relation to the other two cams in such a way that it lifts the pick-reading needles out of contact with the pattern-card and allows their lowering into the pick reading position before 60 the other two cams come in working position, these two cams being disposed in such relation one to another and to the cam for actuating the lifting knife, that during the 65 idle motion of the knife at the forward motion of the machine, the subsequent pick and

at the backward motion the preceding pick is determinative for the position of the lifting hook relatively to the lifting knife.

17. A shed forming machine, comprising two series of warp-thread lifting hooks a 70 lifting knife for each of these series adapted to perform a reciprocating movement and to carry along with it such hooks, means for stopping the movement of these hooks before the knife is reaching its rear dead point, 75 a rotatable cylinder, a paper pattern-card loosely mounted on this cylinder, parallel rows of holes in this pattern-card, the holes in each row being displaced relatively to that on the adjacent rows in the direction of 80 displacement of the pattern-card one row of holes representing the odd picks and the other the even picks, a supporting rocking lever for each of said lifting hooks adapted to hold the hook out of reach of the knife 85 during the idle motion thereof, two driving needles opposite each supporting lever, a pick-reading needle hanging down from each driving needle, these two reading needles being displaced relatively to those of the 90 adjacent pairs in the longitudinal and peripheral directions of the cylinder by the very short distance between two adjacent holes in the pattern-card, two rocking levers opposite the rear end of the driving needles, 95 a rocking lever for supporting these needles and to bring them into and out of reach of the first mentioned rocking levers in dependence on the position of the corresponding pick-reading needle in such a way that each 100 of these two rocking levers is adapted to act upon two driving needles one of which bears upon the one and the other bears upon the other of the hook supporting levers.

18. A shed forming machine as claimed 105 in claim 17, two cams on the same shaft adapted to impart to the two series of lifting knives a reciprocating movement in opposite direction one series relatively to the other, another shaft adapted to revolve at the 110 same speed as the first mentioned shaft, means driven by this shaft to impart to the cylinder supporting the pattern card at each revolution of said shaft an angular movement corresponding to two picks viz, equal 115 to the distance of the two reading needles of the same pair, two pairs of diametrically opposite cams on said second shaft, each pair adapted to act upon one of the rocking levers for actuating the driver needles, the cams 120 of one pair being displaced in peripheral direction relatively to those of the other pair in such a way that at the rear dead center of either of the lifting knives the bell crank levers operated upon by these 125 cams are in position of readiness to act upon the opposite driver needles in accordance with the position of the corresponding pick-reading needle at either direction of movement of the machine.

19. A shed forming machine, comprising thread warp supporting balances adapted to rocking each on a horizontal axis, a hook on each end of this balance pivotally connected therewith, a lifting knife below each of these hooks, a shaft for imparting to these knives a reciprocating movement in opposite direction one relatively to the other, a supporting rocking member for each hook 10 adapted to normally hold the hook out of reach of the knife just before and after this latter is reaching its rear dead center, a perforated paper pattern-card, a cylinder supporting this pattern-card, the holes in 15 the pattern-card being disposed in series arranged in planes at right angles to the axis of the cylinder, two adjacent series of holes being displaced relatively one to another in the direction of the series at a distance 20 equal to the half of the very short distance of two holes of the same series (weft-distance), one series corresponding to the odd picks, the other to the even picks, two pairs of pick reading needles for each pair of 25 lifting hooks, these needle pairs being in the same vertical planes as the series of holes in the pattern-card, the distance between the needles of the same pair being equal to the double weft distance as represented 30 on the pattern-card and the needles of one pair being displaced relatively to that of the other pair in their planes at the weft distance, a driver needle for each pick-reading needle, the two driver needles supporting the reading needles of the same pair lying with one end opposite the same of said hook supporting rocking members and with 35 the other end opposite to different of two rocking levers, means for imparting to the pattern-card by means of the cylinder and 40 after each second pick an intermittent movement by an extent equal to the distance between the pick-reading needles of the same pair (double weft distance), a rocking lever for supporting the driver-needles and to 45 hold the pick-reading needles out of contact with the pattern-card during the displacement thereof, said rocking lever allowing after such displacement the pick-reading needles to drop into pick-reading position 50 and to bring thereby the corresponding driver needles into the path of the opposite rocking lever cams disposed in the reach of these rocking levers and adapted to revolve with the same velocity as the cams for 55 actuating the lifting knives and disposed in such position relatively to one another and to these last mentioned cams that each of the above mentioned hook supporting rocking members of one pair of hooks is, 60 as to its position, controlled by one of said rocking levers at the end of the rearward stroke and by the other rocking lever at the beginning of the subsequent forward or lifting stroke to permit the hook to come into 65 reach of the knife at the subsequent stroke and to be carried along with it at either direction of movement of the machine if the pick-reading needle corresponding to this stroke has entered into one of the holes of 70 the pattern-card.

In testimony whereof I have affixed my signature.

HUGO STÄUBLI.
